UNITED STATES PATENT OFFICE

114,790

DESIGN FOR A COLLAR HOLDER OR SIMILAR ARTICLE

George A. Ingleby, Cranston, R. I., assignor to The Hadley Company, Inc., Providence, R. I., a corporation of Rhode Island

Application February 23, 1939, Serial No. 83,162

Term of patent 7 years

To all whom it may concern:

Be it known that I, George A. Ingleby, a citizen of the United States of America, residing at Cranston, in the county of Providence and State of Rhode Island, have invented a new, original, and ornamental Design for a Collar Holder or Similar Article, of which the following is a specification, reference being had to the accompanying drawing, forming a part thereof.

Fig. 1 is a front view, and Fig. 2 an edge view of a collar holder embodying my new design.

The distinguishing feature of the design is a front member in the form of oppositely extending elongate, substantially parallel side loops closed at their outer extremities.

I claim:

The ornamental design for a collar holder or similar article, substantially as shown and described.

GEORGE A. INGLEBY.
